UNITED STATES PATENT OFFICE.

WILLIAM F. BARNES, OF ROCKFORD, ILLINOIS, ASSIGNOR TO THE W. F. & JOHN BARNES COMPANY, OF SAME PLACE.

DRILLING-MACHINE.

SPECIFICATION forming part of Letters Patent No. 461,253, dated October 13, 1891.

Application filed January 31, 1889. Serial No. 298,214. (No model.)

To all whom it may concern:

Be it known that I, WILLIAM F. BARNES, a citizen of the United States, residing at Rockford, in the county of Winnebago and State 5 of Illinois, have invented a certain new and useful Improvement in Drilling-Machines, of which the following is a specification.

The object of this invention is to construct a drilling-machine in which various speeds 10 may be obtained without stopping the running of the drill or shifting the belt, thereby dispensing with the usual cone-pulleys and, if desired, connecting the drill direct with the line-shafting.

15 The further object of this invention is to so construct a friction driving mechanism, and means for adjusting the tension of the friction applied to adapt it for use for light work.

In the accompanying drawings, Figure 1 is 20 an elevation of a complete drill embodying my invention. Fig. 2 is a partial plan view showing the friction mechanism. Fig. 3 is a vertical central section through the drill-spindle and its friction driving mechanism.

25 The main portion of the drill represented in the accompanying drawings is of the construction shown in Patent No. 285,726, dated September 26, 1883, which consists of the hollow main supporting-column 1 with its upper 30 curved end 2. A platen 3 is supported by the main column 1, and by means of the screw 4, engaging a collar 5, the platen is made adjustable up or down to suit the different kinds of work. The drill-spindle 6 is supported to 35 move in bearings 7 and 8 of the supporting-frame. A handle 9 operates the drill-spindle in its vertical movements. The rope or chain 10 connects a counterbalance-weight with the drill-spindle.

40 The features of my invention relate to the mechanism for driving the drill-spindle and the tool carried thereby, which I will now proceed to explain.

45 In place of the usual bevel gear-wheel employed to impart motion to the drill-spindle I have employed a horizontal plate 11, having a tubular projection 12 depending from its lower face. This plate is held in its working position in the bearings 7 and 13 of the main 50 supporting-frame. A feather 14 is placed in the opening of the tubular projection 12 for

a purpose to appear hereinafter. The bearing 13 is screw-threaded, and a screw-threaded collar 15 is turned therein, as shown in the drawings. A jam-nut 16 is turned on the 55 projecting end of the collar 15. Holes 17 and 18 are provided for the purpose of turning the collar or jam-nut, respectively, as may be required. In the drawings I have shown a babbitt washer 19 placed between the horizontal plate 11 and collar 15, which makes a smooth bearing-surface. The drill-spindle is lengthwise slotted and engages the feather 14, by means of which the spindle is rotated.

A horizontal shaft 20 is supported to 60 revolve in bearings 21 and 22 of the main frame. Upon this shaft is supported a drive-pulley 23, which in this instance is connected by a belt 24 directly with the line-shafting, thereby dispensing with the cone-pulley usually 65 supplied with such machines. Upon this shaft 20 is supported a pulley 25, composed of metal and leather. The metal portion consists of a flange 26, having hubs 27 and 28 projecting on either side thereof. These hubs 70 are centrally bored of a diameter to admit the shaft 20 in a proper manner to slide thereon. A feather 29 engages the lengthwise groove 30 of the shaft 20. A leather disk 31 is placed on the hub 27 and is secured in place 75 thereon by means of a disk 32 and screws 33, passing through the parts and screwed into the flange 26. Upon the hub 28 is placed a collar 34, having a lug 35, which is held in place 80 by the collar 36. Into the lug 35 is secured a 85 rod 37, which passes through a bearing 38 on the main frame. A set-screw 39 or other similar device is screw-threaded into the bearing 38 and comes in contact with the guide-rod 37, and by means of which the rod may be adjusted. Handles 40 project from opposite 90 sides of the collar 34, by means of which the operator may move the pulley 25 along the horizontal shaft 20.

With the parts placed in the position shown 95 in the drawings, motion being imparted to the pulley 23 by means of the belt 24 will impart a like rotary movement to the pulley 25 in the direction indicated by the arrows, which by its friction contact with the disk 11 100 will rotate said disk, as shown in Fig. 2, consequently leaving the drill-spindle in the

proper direction for drilling. The relative position of the pulley 25 with the disk 11 is such as to impart the slowest rotary movement to the disk, thereby admitting of the use of the largest-sized drill.

When the pulley 25 is directly over the center of the disk 11, the countersink 41 in the disk will allow the pulley 25 to revolve without engaging the disk or imparting motion thereto. By means of the handles 40 the pulley 25 is moved across the face of the disk 11, and as it is moved toward the center of the disk the speed of the disk will increase until it has reached its greatest speed, which will be just before it enters the countersink 40. As the speed increases so may smaller drills be used. When the proper speed is obtained for a certain piece of work, it may be retained by means of the set-screw 39, engaging the guide-rod 37. A reverse movement of the drill may be accomplished by moving the pulley 25 past the center of the disk 11. The speed at first will be very rapid and gradually diminishing in velocity.

In using very small drills there is great danger of breaking them; but by means of the screw-threaded collar 15 and its connec-

tion with the bearing 13 the disk 11 may be raised or lowered, thereby adjusting the friction of the pulley 25 with relation to the disk 11, and the jam-nut 16 will hold it when adjusted. The adjustment can be so delicate as to stop the rotation of the drill-spindle, thereby preventing the breaking of the drill should it from any cause become fastened. 35

I claim as my invention—

A drilling-machine consisting of a vertical supporting-frame, a horizontal driving-shaft mounted in its upper portion, a vertical drill-spindle supported by the frame and capable of a vertical and a rotary movement, and friction mechanism forming a connection between the driving-shaft and drill-spindle, that part of the friction mechanism mounted on the driving-shaft made movable in the lengthwise direction of the shaft into and out of frictional contact with the other part, and one of the parts of the friction mechanism having its face of elastic material. 45
